Specification of Letters Patent. Patented Aug. 18, 1914.

Application filed March 28, 1914. Serial No. 827,804.

To all whom it may concern:

Be it known that I, SAMUEL EDWARD BURCHELL, a citizen of the United States, residing at Paterson, in the county of Passaic and State of New Jersey, have invented 5 certain new and useful Improvements in Shovels, of which the following is a specification.

The object of this invention is to provide 10 a shovel blade so constructed that it may be quickly and easily fitted to a shovel whose blade has become worn out or to some other suitable implement, such as a fork, and when so adapted will produce an implement whose 15 blade and handle members are substantially as rigidly associated as the blade and handle of any shovel having these parts secured together by rivets or other permanent means.

Referring to the accompanying drawing, 20 Figure 1 is a perspective view showing the improved shovel blade applied to a shovel whose blade has become more or less worn; Fig. 2 is a rear elevation of what is shown in Fig. 1; Fig. 3 is a side elevation thereof, 25 showing the blade in section; Fig. 4 shows the improved blade applied to a fork; and, Fig. 5 is a rear elevation of what is shown in Fig. 4.

In said drawings *a* and *b* are, respectively, 30 the handle and blade of a shovel whose blade has become more or less worn away, as shown, the handle being received in and riveted or otherwise permanently fixed in the socket of the blade; *c* designates my improved shovel blade, which may be shaped 35 according to the use to which it may be put, but it is preferably somewhat wider than the blade of the shovel *a*—*b* which is to be assembled with the blade *c* as the handle 40 therefor.

To the back of the blade *c* is permanently secured, as by rivets *d*, a transverse metal strap *e* having its intermediate portion elevated or spaced from the back surface of the 45 blade *c*, so that the arch thus produced forms with the blade a socket.

Forming an integral part of the middle upper portion of the blade is a split collar or band *f* having its ends *g* arranged in parallel planes and penetrated by the bolt *h*. The ends of the collar *g* preferably project rearwardly, so that the intact intermediate 50 part of the collar will be located with respect

to the handle where the greatest strength is required; and said ends are adapted to be 55 spread apart to admit the shaft portion of the handle. With the blade *c* thus constructed, the old shovel *a*—*b* as a handle is fixed thereto thus: Its blade *b* is forced into the socket formed by the back of the blade 60 and the strap *e* and then, its handle having been made to be embraced by the band *f*, the bolt *h* is tightened up to clamp the old shovel in place securely as a handle.

The construction shown in Figs. 4 and 5 65 is substantially the same as that in Figs. 1 to 3 excepting that two sockets *i* are formed at the back of the blade *j* and therewith by the strap *k* by bending the strap outwardly between the members of each of two pairs 70 of rivets *l* whereby the strap is secured to the blade. These sockets are then adapted to receive the outer tines of the fork *m*, the shaft of which is clamped by the split collar *n* on the blade *j* having the bolt *o* and being 75 otherwise substantially similar to the collar *f* already described.

To impart increased rigidity to the connection between the blade and its handle, relieving the collar of some of the strain 80 thereon, the blade in either case is preferably formed with a channel in alinement with and adjoining the collar and adapted to snugly receive the shaft of the handle, such channel being produced by bending the 85 metal of the blade forward, as shown at *p* in Figs. 1, 3 and 4 in forming the blade.

Having thus fully described my invention, 90 what I claim as new and desire to secure by Letters Patent is:—

1. A shovel blade having on the back thereof a socket closed at the back and adapted to receive the lower end of a suitable handle member said blade having at its upper end a split collar and means to 95 bind the collar rigidly around the handle member, substantially as described.

2. A shovel blade having on the back thereof a socket closed at the back and adapted to receive the lower end of a suitable handle member said blade having at its upper end a split collar and means to bind the collar rigidly around the handle member, the upper portion of said blade immediately below and alined with the collar having a channel at the back thereof adapted to 100 105

snugly receive said handle, substantially as described.

3. The combination of a shovel blade and an arched piece secured to the back of said 5 blade and forming therewith a socket to receive the lower end of a suitable handle member, said blade having at its upper end a split collar and means to bind the collar rig-

idly around the handle member, substantially as described.

In testimony whereof I affix my signature in presence of two witnesses.

S. E. BURCHELL.
